UNITED STATES PATENT OFFICE.

GEORGE E. HERRMANN, OF MORRISTOWN, AND BENJAMIN W. TUCKER, OF SOUTH ORANGE, NEW JERSEY; SAID TUCKER ASSIGNOR TO SAID HERRMANN.

BARREL.

1,216,804.

Specification of Letters Patent. Patented Feb. 20, 1917.

Application filed February 12, 1912. Serial No. 676,963.

To all whom it may concern:

Be it known that we, GEORGE E. HERRMANN and BENJAMIN W. TUCKER, citizens of the United States, and residents of Morristown, county of Morris, State of New Jersey, and South Orange, county of Essex, and State of New Jersey, respectively, have invented certain new and useful Improvements in Barrels, of which the following is a full, clear, and exact description.

This invention relates more particularly to barrels made from sheet steel or similar metal.

One of the principal objects of the invention is to provide a barrel or other container having a plurality of staves or members each of which is provided with a groove lengthwise of the stave and extending throughout the greater part of its length and along one edge, and a tongue or rib portion along the other edge of said stave, the said tongue portion of one stave being adapted to fit into the groove portion of the adjacent stave, and the tongue and groove portions of the staves so formed that they will be positively interlocked and reinforced by the interlocking action in order that the barrel when assembled will be strong and not liable to collapse under the strain to which such objects are subjected.

Another object of the invention is to provide simple and efficient means whereby the head or heads of the barrel or container may be properly supported and held within the barrel body and the said barrel body materially strengthened at its ends.

A further object of the invention is to provide a joint between the staves or members of the barrel or other container which may be variously formed and the barrel or container made substantially flush on the exterior surface thereof.

A still further object of the invention is to provide a simple and efficient barrel or other container which may be readily made and assembled and in which the members may be detachable.

With these and other objects in view, the invention will be hereinafter more particularly described with reference to the accompanying drawings, which form a part of this specification, and will then be pointed out in the claims at the end of the description.

In the drawings, Figure 1 is an elevation,

partly broken away and partly in section, of one form of barrel embodying our invention.

Fig. 2 is a plan view, partly broken away and partly in section.

Fig. 3 is a detail perspective view of one of the barrel staves or members.

Fig. 4 is an enlarged fragmentary sectional view of the upper part of the barrel.

Fig. 5 is a partial perspective view of one part of a reinforcing ring or member for the barrel head.

Fig. 6 is a fragmentary sectional plan through two of the stave members, showing one form of joint.

Fig. 7 is a similar view showing a slightly different form of joint.

Fig. 8 shows where the joint is not continuous.

Fig. 9 is a sectional view, taken on the line IX-IX of Fig. 8.

Fig. 10 is a sectional view taken on the line X-X of Fig. 8.

Fig. 11 is a sectional view taken on the line XI-XI of Fig. 8; and

Fig. 12 is an enlarged fragmentary section of another form of barrel and means of locking the head to the barrel body.

While we show and describe the invention as applied to a barrel, it will be understood that the invention may be applied to other containers as well as to bilged or similar forms of barrels.

The barrel or container body 10 comprises a plurality of staves or members 11. Each stave is curved and bilged centrally to adapt the barrel to be larger at the central portion as is usual in the ordinary form of barrel to adapt the same when lying on its side to be easily and readily placed on end. The staves or members are each provided along their edges with flanges 12 and 13. These flanges extend the greater part of the length of the staves and project inwardly from the body portion so that when the staves are assembled the outer surface of the barrel will be substantially flush. The flange 12 has a projecting portion 12^a extending lengthwise thereof which forms a rib or tongue. The tongue is forced from the flange and is located between the body portion of the stave or member and the outer edge of said flange, and said tongue in one form extends at an angle with respect to the body of the barrel and the body of the flange. In Figs. 1 to 6, 110

the tongues or ribs extend toward the body portion and are adapted to enter a groove 14 in the flange 13. The groove 14 of each stave is of a size to receive the tongue or rib 13 of the stave next adjacent thereto, and said groove is formed by depressing the body of said flange 13. The flange 13 when depressed will be substantially U-shaped in cross-section so that a part, as 15, overlaps the body of the barrel stave and rests upon the same at the curved portion of the said flange, thus providing a backing for the grooved portion tending to prevent the same from collapsing by any strain that might 10 tend to force the said flange outward or spread or open the joint when the barrel staves or members are assembled. The U-shaped portion of the flange corresponds with the tongue or rib 12^a and by having 20 the rib and grooved flanges at an angle with respect to the body portion they will tend better to interlock and prevent the separation or opening by spreading or otherwise of the flanges at the joint, at the same time permitting the barrel staves or members 25 where desirable to be readily assembled and to be as readily detached in case it is desired to replace one stave by another when injured or for any other purpose. The outer edge of the flange 12 may be provided 30 with an inwardly-extending part or angular portion 16 and the flange 13 may be provided with a similar angular portion 17 in order to strengthen the flange and also avoid 35 a more or less sharp edge as might occur when the barrel is made of the usual thin sheet metal.

The tongues and grooves of the flanges instead of extending angularly and inward 40 toward the body of the staves, as shown in Figs. 1, 2 and 6, the tongues or ribs 18 of the flanges 12, and the groove portions 19 of the flanges 13 may extend outward as shown in Fig. 7, and in either or both cases 45 the angular portions 16 and 17 of the flanges may be extended inward, as at 20 in Fig. 7, to further brace the flanges by the engagement of the part or brace portions 20 with the inner surface of the stave bodies.

50 The flanges of the staves or members do not extend the entire length of the staves or members and at their ends provide shoulders on which rest the heads 21. Both ends of the barrel or container may be similarly constructed, though it will be understood that one end may be formed in any suitable manner and a securing means, such as shown in the drawings, provided at one end only of said barrel or container. As shown, each 55 head 21 has its body portion 22, and at the outer edge thereof, provided with an annular bead or rib 23 from which projects outwardly a flange 24. A ring or member 25 of heavier metal is arranged over the bead 23 of the head and the flange 24, and this

ring or member may be in a plurality of parts or may be a solid and continuous ring as preferred. This ring 25 is provided with an annular groove portion 26 which is adapted to receive a rib or tongue portion 27 formed transversely of the staves at their ends. Each stave has its ends bent outward to pass about the rib 23 of each of the heads 21 also that the rib or depressed portions 26 may fit the grooves of the rings 25. The 75 staves or members have their outer ends bent inward or angularly formed, as at 27, adapted to fit a recess in the outer edge or surface 28 of the ring in order to provide a substantially flush outer surface for the ends 80 of the barrel. If the ring or member 25 is made in sections the outer ends of the staves need not be forced outward to receive the ring members, but if the said ring or member 25 is solid and of one piece, in that case, 85 the outer ends of the barrel staves or members may be sprung outward and then forced inward to engage the ring, as shown best in Fig. 4. The ends of the barrel staves are held to the ring and the several parts locked together at each end of the barrel by a compression band or member 29. This band or member may be annular and split to permit the same to be compressed, and said band is provided with a depressed inwardly extending grooved portion adapted to fit in the transverse groove formed by the ribs 26 of the barrel staves. The band 29 has a skirt portion 31 extending lengthwise of the barrel staves a short distance which is of less 95 diameter than said band so as to provide a shoulder or seat 32. A fastening wire or band 33 is located under the shoulder 32, and a band or wire 34 is located in the groove formed by the rib 31 so that when the wires 33 and 34 are tightened by twisting the ends thereof or otherwise the band or member 25 will be compressed which will hold the ends of the barrel staves, the ring members 25 and the head rigidly together and in such 100 a way as to provide a very strong and effective end for the barrel or container.

The barrel body is provided with transversely extending grooves intermediate the ends thereof which are formed by depressing the barrel staves or members of the container transversely thereof so that when the barrel body is assembled, two substantially continuous grooves will be provided. In one of said grooves a tightening wire or band 115 34^a is located, and in the other groove is a wire or band 34^b so that when said wires are tightened by twisting the ends or otherwise the barrel body will be bound about the same intermediate its ends, serving further 120 to hold the barrel staves or members of the container together.

In Figs. 8 to 11, the construction is somewhat similar to that shown in Fig. 6, except that instead of the ribs and grooves of 125

the flanges being continuous, the interlocking portions are spaced apart in the manner shown, the projecting portions alternating, that is the ribs extend from one flange into a groove of the flange of the next adjacent stave, while the next interlocking portion projects from the flange containing the groove into a groove of the flange adjacent thereto, thus alternating throughout the length of the flanges, though, of course, the said spaced interlocking portions could be located to project from one flange only to enter grooves or similar parts of the flange of the next adjacent stave and still be spaced apart. In these figures, the flange 35 along one edge and the flange 36 along the other edge of each stave are straight for a part of their length, as at 37, and projecting from the flange 36 is a groove 38 and spaced therefrom a tongue or rib 39, thus alternating throughout the length of said flange. The flange 35 is similarly formed with alternating tongues or ribs 40 and grooves 41 separated by the straight portions 35, the grooves of one flange being opposed to the tongues or ribs of the opposed flange. Thus when the barrel or container is assembled, the tongues of one flange will fit into the grooves of the adjacent flange of the next stave.

Fig. 12 shows a somewhat different form of means for fastening the head to the barrel body. The barrel body 42 may be of any suitable construction and may be formed of a plurality of staves as already described. A head 43 may be supported at each end of the barrel body, and this head at its outer edge may have an outwardly extending flange 44. The ring or member 45 either in one piece or comprising a plurality of pieces or parts may be arranged at each end of the barrel body. This ring may be of heavy metal and may be annular in cross-section so as to have a part, as 46, extending lengthwise of the barrel, and a part or flange 47 extending transversely of the barrel and which rests over the barrel head, the vertical portion of the ring or member 45 being cut-away to form a seat for the flange 44 of said head. The ring member 45 is provided with an annular groove adapted to receive depressed portions or ribs 48 extending transversely and at the ends of the barrel staves. The stave ends project outward somewhat from the main body portion and fit about the flange 44 of the barrel heads and also form a shoulder, as at 49 under the head. A compression band or member 50 is arranged around either or both ends of the barrel body, and this band is split to adapt the same to be compressed, and said band has an inwardly projecting rib 51 which is adapted to enter the grooved portions 45 of the barrel staves or members. The band 50 has a skirt portion 52 of less diameter than

the main body of the band and forms a shoulder 53 which is adapted to fit under the shoulder 49 of the barrel staves. A tightening band or wire 54 is arranged under the shoulder 53, and a tightening band or wire 55 is arranged in the groove 51, so that when both wires 54 and 55 are tightened by twisting their ends, or otherwise, the said ring 45, the head 43, and the barrel staves are rigidly held and locked together.

From the foregoing, it will be seen that a simple and effective joint is provided for barrels and other containers which are positively interlocked; that said joint permits the barrel staves or members to be detachably held together in order that an injured stave or member may be replaced by another or for any other reason; that simple means is provided for positively holding the head and parts of the barrel or container together at the ends and for strengthening the barrel or container at said ends; that the invention may be applied to various kinds of containers; and that said barrel or container when constructed in the manner disclosed will be strong, light and may be readily made and assembled and at the same time is inexpensive to manufacture.

Having thus described our invention, we claim as new and desire to secure by Letters Patent:—

1. A barrel or other container, comprising a plurality of members having flanges lengthwise thereof to provide shoulders, heads resting against said shoulders, said heads being provided with an annular bead and with an outwardly projecting flange, a ring of heavier metal adapted to rest against the beaded portion of each head and provided with an annular groove about the same, said members being provided with depressed portions forming ribs transversely thereof and adapted to enter the grooved portions of the rings, a split compression band having an annular ribbed portion fitting the grooved portion of the members, and tightening means for compressing the band about the ends of the staves to lock and hold the members, ring, and head together.

2. A barrel or other container, comprising a plurality of members, a head supported within said members, said members being grooved to form an annular rib when assembled, and a grooved annular member interposed between the ends of the members and the head, the grooved portion thereof adapted to receive said annular rib and means for binding the parts together.

3. A barrel or other container, comprising a plurality of staves having transversely extending ribs, a head located within said staves, said head being provided with an annular bead and with an outwardly pro-

jecting flange, a ring of heavier metal adapted to rest against the beaded portion of the head and provided with an annular groove about the same adapted to receive the ribs 5 of the staves, and a split compression band having an annular ribbed portion fitting the grooved portion of the ribs of the staves.

4. A barrel or other container, comprising a plurality of members having flanges 10 lengthwise thereof to provide shoulders, heads resting against said shoulders, said heads being each provided with an annular bead and with an outwardly projecting flange, a ring of heavier metal adapted to 15 rest against the beaded portion of the head

and provided with an annular groove about the same, said members being provided with a depressed portion forming a rib transversely thereof and adapted to enter the grooved portions of the annular rings, and 20 a split compression band having an annular ribbed portion fitting the grooved portion of the members.

This specification signed and witnessed this tenth day of February A. D. 1912.
